UNITED STATES PATENT OFFICE

2,242,357

COMBINED WARDROBE AND CRIB

Samuel Kroll and Nathan J. Kroll, Chicago, Ill.

Application July 21, 1939, Serial No. 285,644

3 Claims. (Cl. 5—100)

This invention has as its principal object the provision of a combination wardrobe and crib structure.

Another important object is the provision, in an infant's crib of a wardrobe drawer at the bottom of the crib and a drop-side for the crib arranged to fold in a certain manner so as not to interfere with the drawer when the drop-side is lowered for access to the crib.

Other objects, advantages and novel aspects of the invention reside in certain details of construction and the arrangement of the various parts of the illustrative embodiment described hereinafter in view of the annexed drawing, in which:

Fig. 1 is a perspective of the improved crib and wardrobe structure;

Fig. 2 is a vertical section through the drawer and drop-side as seen in the direction of line 2—2 of Fig. 1;

Fig. 3 is a fragmentary cross sectional detail through the drawer and mounting rail looking in the direction of line 3—3 of Fig. 2;

Fig. 4 is a perspective fragment of one inside end wall of the crib and drawer mounting means thereon;

Fig. 5 is a perspective fragment of the wardrobe drawer.

The embodiment shown in Fig. 1 includes a crib structure having opposite sides one of which is a so-called drop-side 15 adapted to be raised and lowered on mounting rods 16. Two drop-sides may be employed if desired.

Mounted beneath the mattress of the crib is a wardrobe drawer 17, provided with opposite faces and handle means 18 (Fig. 2), and mounted to slide on rails 19 secured on the inner side of the opposite end walls 20 of the crib (Figs. 2 and 4). The drawer is provided with a dust panel or top 21 which slides in interior grooves 22 at the top thereof.

One of the features of the invention is the non-interfering drop-side structure which permits the side or sides to be lowered without interference with the drawer. This structure includes the provision of a side wall consisting of hinged joined sections 15 and 15a, one of which (lower section 15a) is pivotally mounted as at 15b on dowels or pins extending from the lower rail thereof into the crib posts, and the other of which, that is, the main side section 15, is slidably mounted on the crib by the means or rods 16.

The hinged connection between the side sections 15 and 15a is preferably effected by con-

cealed hinges 15c (Fig. 2) on the inner sides of the meeting rails of the sections.

Thus, in manipulating the improved structure, the side or sides of the crib may be dropped from the raised position of Fig. 1 by pressing down on the upper or main drop-side section 15, which will cause the same to slide downwardly on rods 16 and tilt outwardly of the crib. The mounting means 16b is loosely fitted to permit this action which occurs by virtue of the hinged connection 15c with the lower section 15a, the latter rocking outwardly of the crib on its pivotal mounting 15b. The outward movements of the section 15 and 15a are defined by the dash-dot line of Fig. 2.

As a result of the foregoing arrangement, it is of no concern whether the drawer is open or closed at the time the drop side is lowered, the advantage in which is obvious.

20 The various advantages and objects of the invention may be accomplished by modifications of the particular embodiment specifically described herein, and it is intended that the appended claims shall include all equivalent arrangements fairly coming within their call.

Having thus described our invention, what we claim as new and desire to protect by Letters Patent is:

1. In a crib, a drop-side structure comprising a main upper side member and an auxiliary side-forming member disposed therebelow, means mounting the upper portions of said main member for vertical sliding movement on said crib, means hingedly joining the lower portion of said main member to the upper portion of said auxiliary member and means mounting the lower portion of said auxiliary member for pivotal movement on said crib, said main and auxiliary members coacting such that a depressing force applied to said main member will lower the same and effect pivotal movement of the lower portions thereof outwardly of the crib by pivotal action of said auxiliary member.

2. In a crib, a drop-side structure including upper and lower side sections and means hingedly joining the same for movement relative to a horizontal axis, coacting bracket and slide rod means on said crib and upper portion of said upper section mounting the latter for vertically sliding movement, means pivotally mounting that part of the lower side-forming section which is opposite its hinged connection with the upper section for pivotal movement on said crib, whereby said upper section may be depressed and said

lower section will pivot to swing the lower portion of the upper section outwardly of the crib.

3. In a crib, a drop-side structure comprising, in combination, upper and lower side sections, means mounting the upper part of said upper section for vertical movement and permitting relative pivotal displacement of the lower portions of said upper section in a direction outwardly of the crib, means mounting the lower portion of said lower section for pivotal movement in a direction outwardly of the crib, and means operatively linking the lower and upper portions respectively of the upper and lower sections for movement together such that downward

movement of the upper portions of said upper section will effect pivotal movement of said lower section with a consequent outward movement of the lower portion of the upper section as a result of the operative linkage thereof with the lower section, whereby the lower portions of the upper section will be prevented from descending below a certain level when the upper section is lowered from a normally raised position in which the upper and lower sections are aligned in a substantially vertical plane.
